ELECTROMAGNETIC ACTUATOR

Willis H. Gille, St. Paul, Minn., assignor to Minneapolis-Honeywell Regulator Company, Minneapolis, Minn., a corporation of Delaware

Application November 16, 1949, Serial No. 127,607

2 Claims. (Cl. 175—338)

1

My invention relates to electromagnetic actuators and more particularly to improvements in actuators of the pivoted armature and plunger type which substantially eliminate the noise of operation of the actuator and rebound of the armature or plunger.

While actuators of the pivoted armature or movable plunger type are old, they generally have a common disadvantage in that the engagement of the armature with a cooperating core or a plunger with a cooperating stop element produces undesirable noise and sets up a tendency for the armature to rebound thereby adversely affecting its controlling operation. The present invention provides in an actuator of this type a core structure having a magnetic circuit in which a portion to be engaged by the armature upon magnetic attraction between the armature and core structure is movable relative to the remainder of the circuit without introducing any substantial variation in the magnetic circuit to effect continuous attraction between the parts and elimination of the shock and noise of operation.

It is therefore an object of this invention to provide a simplified and improved electromagnetic actuator in which noise of operation and rebound is absorbed.

It is also an object of this invention to provide a simplified stop structure for an electromagnetic actuator in which attraction between the parts remains unchanged upon operation of the device.

These and other objects of this invention will become apparent from a reading of the attached specification and together with the drawings in which:

Figure 1 is a plan view of the electromagnetic actuator,

Figure 2 is a section of the plan view of Figure 1 showing the relationship of parts,

Figure 3 is a side elevation view in section of the actuator, and

Figure 4 is a side elevation view of another embodiment of this invention shown in section and disclosing the relationship of the parts.

My improved electromagnetic actuator is shown in the drawings in the form of a clapper-type electromagnet or relay having a magnetic core structure which includes a stationary core member 10, generally L-shaped in form having a main or base portion 11 with a plurality of upstanding or transversely extending portions 12, 13. The upstanding portions 12, 13 are separated into a centrally located portion 12 upon which an armature 15 is adapted to be pivoted and a pair of side portions 13 which serve as backstops for the

2

armature in a manner later to be described. Magnetic core structure 10 including the main portion 11 and upstanding portions 12 and 13 as well as armature 15 are made of a magnetic material of relatively good permeability, such as soft iron, to provide a continuous magnetic circuit.

Armature 15 is generally bar-shaped in form and has attached thereto at its pivoted extremity a brass mounting plate 16 which is secured to the 10 armature 15 through rivets 17 and a reinforcing plate 18, all pieces being made of a non-magnetic material. As best shown in Figures 1 and 2, the non-magnetic mounting plate 16 has a pair of notches 20 therein and a centrally located aperture 21 the purposes of which will become evident as the disclosure proceeds. Notches 20 of plate 16 receive projecting guide members 22 of a mounting plate 23 which is attached to upstanding portion 12 of core member 10. Mounting 15 plate 23 is attached to upstanding portion 12 by any suitable means, such as by rivets, and may be made of any material such as iron or brass. Plate 23, with the exception of the guide pins 22, is so positioned on the upstanding member 12 20 that it terminates below the upper edge of the upstanding portion 12 so as not to be in contact with the armature 15. The projecting guides 22 are disposed to one or the other side of the main body of the armature 15 and fit into the slots 20 30 in the brass mounting plate 16 to guide the armature in its pivotal movement. The upstanding portion 12 of the core structure 10 is beveled as at 25 and engages the armature 15 in a knife-edge engagement. As previously noted, brass mounting plate 16 has a centrally located notch on 35 aperture 21 so provided that the upstanding portion 12 of core structure 10 can directly engage the armature 15 to provide a continuous magnetic circuit at this point.

The lower extremity of mounting plate 23 has a transversely extending flange 26 designed to receive and anchor one end of a spring 27, the opposite extremity of which is anchored in a notch or aperture 28 in the extremity of armature 15. In this manner the armature 15 is biased to an open position or biased for counter-clockwise movement about the pivot formed between the upstanding portion 12 and the armature 15. Side sections 13 of the core structure project up to substantially the same level as the centrally located upstanding portion 12 and are spaced to receive the extremity of the armature to provide a backstop therefor. Further, these portions of the core structure provide a 45 parallel magnetic circuit for the core structure 50 55

which is continuous or without an air gap when the up armature is in an open or deenergized position.

Armature 15 at its free extremity carries a plunger 30 made of a plurality of laminations of magnetic material and attached to the armature proper by means of rivets 31. Plunger 30 extends transversely of the main body of armature 15 and carries a short circuited conductor or shading coil 32 embedded in its free extremity. The plunger 30 is further disposed within the confines of a coil 33 mounted on an insulating bobbin 34 and secured to the main body portion 11 of core structure 10. Coil 33 is mounted on the main portion 11 of core structure 10 by means of a brass sleeve 35 which extends through an aperture 36 in the portion 11 of core structure 10, the sleeve being turned or crimped over at its extremities to securely mount the coil to the core structure 10 and align the coil with the aperture 36 and armature plunger 30.

The magnetic circuit for core structure 10 is completed from the plunger 30 of armature 15 through a magnetic bridging member 40 disposed concentrically with the aperture 36 in portion 11 of the core member and abutting against the core member at its raised edge 41. Bridging plate 40 is mounted on the core structure 10 by means of a spring member 42 to which the plate is riveted as at 43. The free extremity of spring 42 is secured to the portion 11 of the L-shaped core member 10 by means of a screw 44 which is threaded into the core member. A spacer 45 is provided between the spring and core member such that the spring will urge the bridging plate into engagement with the core member 11 at all proportions of the raised surface 41.

In operation, the energization of coil 33 sets up flux lines within the magnetic circuit of the core structure which traversed the magnetic circuit through the plunger 30, armature 15, the upstanding portions 12, 13 of the core structure, the main portion 11 of the core structure, the bridging plate 40, and through the air gap back to the plunger 30. A magnetic attraction will be set up by the circulating flux lines such that the armature 15 and plunger 30 will be drawn further into the confines of coil 33 until it engages the stop member 40. As the plunger 30 travels toward its energized position, the force of attraction between the stationary and movable parts of the magnetic circuit is increased and the momentum of the plunger and armature as it engages bridging plate 40 will cause this bridging plate to move away from contact with the main portion of the core structure. In so moving, the bridging plate will substantially absorb the momentum and noise of engagement of the plunger with itself and the plunger will continue to be attracted to the bridging member. This magnetic attraction between the plunger and bridging plate will cause the plunger to remain in engagement with the bridging plate and hence the armature in the energized position of the actuator as the momentum is absorbed and the plate returns to its normal position. Shading coil 32 carried by the plunger 30 operates in the conventional manner to set out an out-of-phase flux such that an A. C. hum or chatter caused by the A. C. energization of the coil will be overcome. Displacement of the bridging plate 30 from core member 10 is not of sufficient magnitude to vary the characteristics, that is, the reluctance of the magnetic circuit substantially, and hence continuous attraction of the plunger is

obtained thereby eliminating any rebound other than the movement of the plate and plunger back to the normally energized position wherein the bridging plate 40 is in contact with the core structure 10.

Species of Figure 3

The embodiment shown in Figure 3 is similar to that of Figure 2 with the exception of the arrangement of the bridging plate 50 and the modification of plunger 51 of the armature 15. Bridging plate 50 takes the form of a multi-part bridging or stop member having a plurality of inner bridging plates 53 one edge 56 of each of which is positioned in notches 57 in the lower portion of core structure 10 and an outer bridging plate 54, the outer bridging plate being riveted to the spring member 42 which in turn is mounted on the core structure 10 through the screws 44 and spacer 45 in the manner described in connection with Figure 1.

Plunger member 51 which is attached to armature 15 of the actuator is similar to plunger 30 being made of a plurality of laminations of magnetic material riveted together and attached to the armature through rivets 31. Plunger 51 differs from plunger 50, as can be seen in Figure 3, in that a central extended portion 55 of the plunger 51, encircled by the shading means 32, is extended for reasons which will be later noted.

In operation, the actuator of Figure 3 operates in a manner similar to that of Figure 2 differing therefrom only in the fact that the inner stop members 53 operate to maintain continuous engagement of the bridging plate with the core member 11 after plunger 51 engages the bridging plate 50. The bridging plates or stop members 53 are separated to provide an opening through which the central or extended portion 55 of the plunger 51 extends as the plunger is drawn further into the confines of coil 33. This extended portion strikes the outer bridging plate 54 and at the same time the remaining portion of the plunger engages the plurality of stop members 53 to rock those members within the notches 57 or guides 57 with respect to the core maintaining contact between the core member 11 and the bridging plates 53, 54. In this manner a continuous circuit is obtained and no further air gap is inserted in the magnetic circuit. The bridging plates 53 are held in position with respect to the magnetic core structure by virtue of the edges 56 within the notches 57 and the biasing effect of outer plate 54 through the operation of spring 42. This stop member similarly absorbs the momentum and noise of engagement between the armature and the remaining portion of the core structure providing for substantially maximum magnetic attraction between the stationary and movable portions of the magnetic circuit.

While the disclosure herein is related to pivoted armature type actuators and the present teaching is particularly applicable to such an actuator, it is to be understood that a simple plunger type actuator with an appropriate magnetic core structure can utilize the teaching herein by a substitution of the movable stop member for the conventional stationary type stop. The present disclosure is, however, intended to be illustrative only and the scope of the subject invention is to be determined only by the appended claims.

I claim:

1. In an electromagnetic actuator, a magnetic core structure including a core member having an upstanding portion and a transversely extending portion with an aperture in said transversely

extending portion, a hollow energizing coil for energizing said core structure, means including a non-magnetic sleeve member securing said hollow coil to said core member in alignment with said aperture, armature means including a plate of magnetic material pivotally mounted on said upstanding portion of said core member and a plunger of magnetic material attached at one extremity thereof extending normal to said plate and into the confines of said coil, said armature means being adapted to be pivoted about said upstanding portion of said core member with said plunger of said armature means moving within the confines of said hollow coil and out of physical contact therewith, a plate of magnetic material positioned in bridging relationship over said aperture in said transversely extending portion of said core member, means including a spring of non-magnetic material mounting said plate on said transversely extending portion of said core member for movement relative thereto, said core structure being energized with a magnetic flux which flows through said core member said armature means and said plate causing said plunger to be attracted toward and into engagement with said plate, said mounting means for said plate permitting movement of said plate relative to said core member to absorb the impact of said engagement in such a manner that the bridging relationship and the magnetic flux flow within said core structure is substantially maintained.

2. In an electromagnetic actuator, a magnetic core structure including a core member having an upstanding portion and a transversely extending portion with an aperture in said transversely extending portion, a hollow energizing coil for energizing said core structure, means including a nonmagnetic sleeve member securing said hollow coil to said core member in alignment with said aperture, armature means including a plate of magnetic material pivotally mounted on said upstanding portion of said core member and a plunger of magnetic material attached at one extremity thereof extending normal to said plate and into the confines of said coil, said

armature means being adapted to be pivoted about said upstanding portion of said core member with said plunger of said armature means moving within the confines of said hollow coil and out of physical contact therewith, a plurality of members of magnetic material normally disposed outside of said aperture in said transversely extending portion of said core member and covering said aperture in a bridging relationship therewith, means mounting said plurality of members on said transversely extending portion of said core member for movement relative thereto, said core structure upon energization of said coil being energized with a magnetic flux which flows through said core members, said armature means and said plurality of magnetic members causing said plunger to be attracted toward and into engagement with said plurality of magnetic members, said mounting means for said plurality of magnetic members permitting movement of said members relative to said core member upon engagement of said plunger with said magnetic members to absorb the impact thereof in such a manner that said bridging relationship and flow of flux through said core structure is substantially maintained.
